PANEL LIGHT SOCKET ASSEMBLY

Louis R. Wanner, Warren, Pa., assignor to Sylvania Electric Products Inc., a corporation of Massachusetts

Application March 23, 1953, Serial No. 344,035

6 Claims. (Cl. 339—126)

This invention relates to light sockets.

In particular it relates to such sockets of very small size adapted to be applied to instrument panels.

In these sockets it is highly desirable that the construction shall be simple with as few parts as possible and yet provide for proper mounting of the sockets on the panel and for proper electrical contact with the bulb inserted into the socket. It is also further desirable to make the parts of molded and stamped portions only so that the sockets may be made cheaply. It is to satisfy these requirements that the novel socket herein described and illustrated in the accompanying drawing has been contrived. The subject matter herein is an improvement on the socket disclosed and claimed in an application filed by Patrick Alessi, Serial No. 343,949, filed concurrently herewith.

In the drawings:

Fig. 1 is an exploded view of the socket, a portion being in section together with a view of a conventional bulb utilized with the socket.

Fig. 2 is a section through an assembled socket and bulb mounted on a panel.

Fig. 3 is a rear view of a portion of my socket.

Fig. 4 is a section through a modified form of socket mounted on a panel.

Referring to the drawings more in detail, it will be noted that the socket consists of but three parts, a molded insulating shell section 10, a metallic section 12 press fit or molded into the shell and a metallic plate or base member 14 serving as a means to hold the bulb in place, make electrical contact therewith and act as a means for enabling the attachment of a wire thereto.

The molded shell 10 may be made of any suitable material such as a thermosetting or thermoplastic resin. It is molded to have a recess 16 and a circular opening 18, functioning to receive the inner combined panel attaching and bulb contact means 12. The recess portion 16 may have a portion of it partake of a hexagonal formation or may merely have opposed chordal walls 20, 20 cooperating with a hexagonal formation 22 on the contact means 12. The contact means has the said hexagonal formation 22 and a hollow cylindrical neck portion 24, the neck portion snugly fitting within the opening 18 of the shell with the outer end of the neck portion flared over the shell at 26 to ensure retention of the contact means within the shell. The neck portion is further reduced at 28 to provide a projection which may be inserted through a hole in the panel from the rear thereof. The height of the reduced section is designed so that the free edge thereof protrudes slightly beyond the front face of the panel whereat the edge may be spun over the panel or otherwise flattened to hold the socket in place. To permit easier spinning of the edge or flattening over the face of the panel, the inner bevelled portion 29 is provided. To prevent rotation of the socket with respect to the panel, the latter may have a radial keyhole slot cut therein so as to allow some metal of member 12 to engage the

slot during the spinning operation. A circular recess or channel 30 is provided on the shoulder between the wider portion of the neck and the reduced portion to allow for easier formation of the edge 26 and to provide better electrical contact of the socket with a conductive panel, if the panel be of metal, and if the panel forms part of the electrical circuit. That is so since the thin edge may be squashed against the panel to conform to irregularities of the panel surface.

10 The shell on its exterior has a shouldered portion 38.

The plate or base member or contact means 14 is in the form of a planar annulus with an integral soldering lug 39. Further it has two arcuate walls 40 perpendicular to the plane of the annulus and each of these walls has two lugs 42 bent over the shouldered portion 38 to effect tight association of parts. To enable a rounded formation of the juncture between the vertical walls and the main body portion to be utilized whereby the plate is not weakened by a sharp bend at the junction and to prevent

20 chipping away of the edge of the molded shell section when the member 14 is applied and fastened to the molded portion, a second shouldered portion indicated as 44 is molded into the insulating section. Within the annular ring portion of the member 14 is struck out a nib 46

25 to engage within a radial slot 47 in the molded shell section to thereby prevent relative rotation of the shell and plate member 14. The center portion of the annulus has struck out therefrom an internally threaded boss 48 extending toward but terminating short of the face of the hexagonal portion of the contact member 12. The bulb is intended to be threaded into the boss 48. The bulb has the threaded portion 50 as one terminal and a ring member 52 as the other. The ring member and threaded portion are insulated from one another by a suitable insulating collar 54. When the bulb is screwed into the plate member the ring member 52 engages into firm electrical contact with the hexagonal portion 22 to thereby complete the circuit between the electrodes 12 and 14.

30 In the modification of Fig. 4, instead of flaring the thinned portion 29 over the panel, a more conventional arrangement such as an exteriorly threaded neck 56 and decorative nut 58 may be employed.

35 While I have disclosed a specific embodiment of my invention, it is obvious that it may partake of various forms and it is therefore intended that the following claims should not be limited by the specific form of invention herein but only by the limitations imposed therein.

40 What I claim as my invention is:

45 1. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, said first contact member being stepped in external diameter with the largest diameter portion engaging one inner wall of the shell and the edge of the next stepped portion flared over and in contact with the opposed outer wall of the shell.

50 2. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, the neck portion of said first contact member being stepped to provide said extending neck portion and a second portion of larger diameter, said first contact member also having a flange on said larger

55 60 65 70 75 80 85 90 95

diametered portion, the first contact member being secured to said shell by engagement of the flange with an inner face of the shell and by a flaring of the material of said member at the stepped portion over the opposed outer face of the shell.

3. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, the neck portion of said first contact member being stepped to provide said extending neck portion and a second portion of larger diameter, said first contact member also having a flange on said larger diametered portion, the first contact member being secured to said shell by engagement of the flange with an inner face of the shell and by a flaring of the material of said member at the stepped portion over the opposed outer face of the shell, there being a channel surrounding the neck portion in the surface of the material between the two stepped portions.

4. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, the neck portion of said first contact member being stepped to provide said extending neck portion and a second portion of larger diameter, said first contact member also having a flange on said larger diametered portion, the first contact member being secured to said shell by engagement of the flange with an inner face of the shell and by a flaring of the material of said member at the stepped portion over the opposed outer face of the shell, the flange being noncircular in shape and the shell having a recessed portion also noncircular in shape to house the flange, thereby to prevent relative rotation between the first contact member and shell.

5. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, said shell being stepped exteriorly and said second contact member comprising a base member and lugs on said base member bent over a stepped portion of the shell, there being registering interlocking formations on opposed faces of the shell and base member to prevent relative rotation therebetween.
- 10 6. A socket comprising an insulating shell, a metallic electrical contact member therein, said member having a hollow neck portion extending a distance beyond an exterior face of the shell for securing the socket to a panel support, and a second contact member on said shell spaced so as to be out of contact with said first member and provided with a threaded bore in registration with said hollow neck portion, said shell being stepped exteriorly and said second contact member comprising a base member and lugs on said base member bent over a stepped portion of the shell, there being a radial slot in the face of the shell opposed to the second contact member and a protuberance on the base member in position to lie within the slot to prevent relative rotation between the shell and the base member.
